CLAIM

The ornamental design for a hand warmer, as shown and described.

DESCRIPTION

FIG. 1 is a front perspective view of a hand warmer, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top perspective view showing the hand warmer in a disassembled state;

FIG. 10 is a bottom perspective view showing the hand warmer in a disassembled state; and,

FIG. 11 is an enlarged detail view of area 11 in FIG. 2. The broken lines in the drawings illustrate the portions of the hand warmer, which form no part of the claimed design. The dash-dot-dash broken lines encircling the enlarged views are for annotative purposes only and form no part of the claim thereof.
